UNITED STATES PATENT OFFICE.

WILLIAM H. McCLELLAND, OF HUNTINGDON, PENNSYLVANIA, ASSIGNOR, BY MESNE
ASSIGNMENTS, TO ROY P. M. DAVIS, OF MOUNT UNION, PENNSYLVANIA.

SPLASH HOOD.

Application filed December 15, 1924. Serial No. 755,940.

To all whom it may concern:

Be it known that I, WILLIAM H. McCLELLAND, a citizen of the United States of America, residing at Huntingdon, in the county of Huntingdon and State of Pennsylvania, have invented certain new and useful Improvements in Splash Hoods, of which the following is a specification.

My invention relates to splash hoods for brick making machines and more particularly, machines for making silica brick.

In silica brick making machines it has been found that the material from which the bricks are made seriously interferes with the mechanism if the material splashes over the moving parts during the mold filling operation. The present invention overcomes this objection to a marked degree.

In the accompanying drawings forming a part of this specification:

Figure 1 is a side view of the splash hood operating mechanism.

Figure 1^a is a side elevation of the splash hood in raised position.

Figure 2 is a top plan view of the splash hood operating mechanism.

Figure 3 is a vertical section showing the splash hood in lowered position.

Figure 4 is a sectional view taken on the line 4—4 of Figure 1^a, and

Figure 5 is a sectional view taken on the line 5—5 of Figure 1^a.

Referring more particularly to the drawings, wherein like reference numerals denote corresponding parts throughout the several views, the numeral 1 indicates a part of the reciprocating carriage of a brick making machine (not shown) to which are pivoted as at 2, mold supports or arms 3 upon which is a bottom plate 4 upon which the mold 5 rests. The carriage 1 is adapted to be moved in any approved manner beneath a brick making material feed hopper or chute 6 for the purpose of filling the mold 5.

When a charge of material (not shown) is discharged from the hopper 6 into the mold 5, the material has a tendency to splash or scatter over the adjacent moving parts of the brick making machine. This splashing is controlled by means of a splash hood 7 arranged beneath and in vertical alignment with the hopper 6.

The splash hood 7, which is substantially

rectangular in shape, comprises end walls 55 8 and side walls 9. The hood is pivotally connected to the frame 10 of the brick making machine by means of an arm 12, pivoted to a rod 13, having a threaded end 14, adjustably connected to a bracket 15 carried by the splash hood, a nut 40 locking the rod in its adjusted position. The arm 12 is connected to a short shaft 11 which passes through the frame 10 and a housing 18 which receives the end of the arm, a filler block 19 insures a tight fit between the parts. One of the side walls 9 of the splash hood is outwardly flared at its bottom as at 16, and the bottom edges of the end walls are cut away as at 17 to snugly receive the mold 70 when the hood is lowered over the top of the mold.

The splash hood is first elevated to Figure 1^a position to permit the mold to be reciprocated therebeneath to filling position, 75 and it is then lowered to Figure 3 position just prior to the delivery of a charge of mud from the hopper 6 to the mold. The excess mud or material will splash against the inner walls of the splash hood and then drop down at the sides of the mold, upon an endless conveyor, not shown, which returns the same to the hopper 6. It will be noted that the splash hood is somewhat wider than the mold so that the excess mud 85 may escape, also that the flared portion 16, of one of the side walls of the hood likewise facilitates this action.

Secured to the frame 10 of the machine are a pair of angle brackets 20 in which is 90 mounted a small shaft 21, to which is pivoted a pair of arms 22, spaced apart by spacing blocks 23 and 24. The spaced arms 22 are connected with the arm 12 by means of a connecting rod 25. Consequently when the arms 22 are raised and lowered about the shaft 21 as an axis, the splash hood will also be raised and lowered.

A cam 31, mounted on a cam shaft 26 secured in bearings 27 in the frame 10, engages a grooved roller 28 mounted on a shaft 29, and thus supports the arms 22. Upon each rotation of the cam shaft 26, which is constantly driven from any suitable source of power (not shown), the roller 28 engages in the cut away portion 30 of a cam 31, thus causing the arms 22, the arm 12 and the splash hood to drop. This action takes

place just prior to the feeding of a charge of mud or material to the mold, and the hood is almost immediately lifted as the shaft 26 and cam 31 thereon continue to 5 rotate, and the roller 28 rides out of the cut away portion 30 of the cam. It will be understood that the movement of the carriage which carries the mold is timed with the movement of the splash hood to the end 10 that the hood will be raised to clear the mold when the latter is moved beneath the hood.

From the foregoing, it is thought that the construction, operation and many advantages of the herein described invention will be apparent to those skilled in the art, without further description, and it will be understood that various changes in the size, shape, proportion and minor details of construction 20 may be resorted to without departing from the spirit or sacrificing any of the advantages of the invention.

Having thus fully described my invention, what I claim as new, and desire to secure 25 by Letters Patent, is:—

1. In a brick making machine, a movable mold carriage and mold therefor, a hopper for feeding brick making material to the mold, a splash hood arranged beneath the

hopper and in alignment therewith, and 30 means for raising and lowering said hood.

2. In a brick making machine, a movable mold carriage and mold therefor movable to and from filling position, a hopper above the filling position for feeding material to 35 the mold, a splash hood arranged beneath the hopper and in vertical alignment therewith, and means for lowering the splash hood operable when said mold reaches the filling position.

3. In a brick making machine, a mold support and mold therefor, means for feeding material to the mold, and a vertically movable splash hood in vertical alignment with 40 said material feeding means.

4. In a brick making machine, a mold support and mold therefor, means for feeding material to the mold, a splash hood having a cut away portion adapted to fit over and receive said mold, and means for raising and 50 lowering said hood.

In testimony whereof I affix my signature in presence of two witnesses.

WILLIAM H. McCLELLAND.
